TRACK SHOE

Ralph A. Hyde, Newton, Mass., assignor to A. R. Hyde & Sons Company, Cambridge, Mass., a corporation of Massachusetts

Application December 1, 1958, Serial No. 53,595

Term of patent 14 years

(Cl. D7—7)

Figure 2 is an elevation of the other side of the same.

I claim:

The ornamental design for a track shoe, as shown.
